UNITED STATES PATENT OFFICE.

WILLI FRANCK, OF ROCK ISLAND, ILLINOIS.

VISE.

1,407,743.

Specification of Letters Patent. Patented Feb. 28, 1922.

Application filed November 8, 1920. Serial No. 422,453.

To all whom it may concern:

Be it known that I, WILLI FRANCK, a citizen of the United States, residing at Rock Island, in the county of Rock Island and 5 State of Illinois, have invented a new and useful Vise, of which the following is a specification.

My invention relates to improvements in work bench vises in which a removable jaw 10 anchored to a base mounted upon a screw is caused to advance or retreat by the operation of the screw, thereby creating a relation between the removable jaw of such base and a corresponding jaw anchored in alignment therewith by plate means in the surface of the work bench, in such manner as to provide means of holding material being worked upon between such jaws securely during the work. The object being to provide 15 removable jaws variably stationed apart of size suitable to the varying thickness and length of the material being worked upon; and the work desired and to provide removable jaws which grasp uniformly, remain stable and which may be changed quickly and of varying sizes suitable to the work; and to provide means in the combined base and jaw construction of relieving the screw of the vise from the strain of the 20 clamp or the strain of the pressure exerted upon the article worked upon; and to provide a removable jaw and base so suited to each other as to prevent the jaw from becoming displaced under the vibration created by the work upon the article worked upon; and to provide a vise in which the screw may be used at the end of the bench without increased protrusion; and to provide a vise suitable for use in large or small 25 work yet of a size so diminutive that in attaching it to any work bench it not only does not interfere with the other uses to which the bench may be put, but does not weaken the strength or mar the beauty of the work 30 bench.

I attain these objects by the mechanism illustrated in the accompanying drawings, in which:

Figure 1 is a top plan view of the vise, 50 jaws and jaw plates mounted on the work bench in working position.

Fig. 2 is a sectional view of the major plate taken on line "2—2" of Fig. 3.

Fig. 3 is a side elevation of the vise having 55 the several parts attached in working position.

tion and disclosing in dotted lines the working mechanism of the parts.

Fig. 4 is a perspective view of the traveling base.

Fig. 5 is a perspective view of the movable jaw clamp.

Fig. 6 is a perspective view of the point end brace of the major plate.

Fig. 7 is a perspective view of the stationary jaw clamp.

Fig. 8 is a perspective view of a minor jaw plate.

Similar letters refer to similar parts throughout the several views.

The major plate 1 is composed of an oblong flat plate 1, having one of its ends right-angularly square and flanged to a right angle 2, the other end rounded. In the center of major plate 1 I provide a right-angularly disposed oblong slot 1^a extending from a point suitably near the flanged end 2 to a point suitably near the rounded end. The oblong slot 1^a having provided in the end 70 nearest the rounded point of plate 1, a right-angular oblong offset 1^b of size conformable to the neck 11^b of stationary clamp 11. In the rounded end of major plate 1, I provide suitable milled holes, counter-sunk for the insertion of means suitable for securing to such end boxing brace 4, and at the sides 75 and ends of major plate 1 I provide multiple holes 1^c for the insertion of means for securing the same to the work bench.

The under side of said major plate 1 is also provided at either side of the oblong slot 1^a with right-angularly disposed flanges 3 which serve as a guide channel in which the flanged top 9^b of jaw base 9 travels which jaw base 9 is operated on screw 5 and which flanges 3 extend toward the round 80 point of plate 1, suitably longer than oblong slot 1^a to admit the making of another oblong offset 1^b in the plate 1 at the end of slot 1^a 85 for the purpose of inserting stationary clamp 11.

The flanged end 2 of major plate 1 partly covers a suitable shoulder boxing 2^a stationed connectedly to the flanges 3 the edges of plate 1 and flange 2 extending flangedly beyond the shoulder boxing 2^a, the corner of 90 the shoulder boxing 2^a being cut away suitably to permit the operation of boss 5^b of screw 5.

In the lower portion of the shoulder boxing 2^a, is provided a boxing hole extending 110

through flanged portion 2^b and flange 2 suitable to admit the screw stem 5^c of screw 5, forming a boxing for the screw stem 5^c.

For operation I provide a screw 5 having its point 5^a and stem 5^c journaled, and also having a boss 5^b and a screw stem head 6 provided with a suitable handle 8 mounted thereon, and secured thereto by screw means 7, said screw 5 being for the purpose of 10 operating the jaw clamp traveling base 9, and the threads thereof conformable to the threads 9^a thereof.

At the point end and on the under side of major plate 1, I provide a boxing brace 4 attaching flush against flanges 3 and secured to plate 1 by any suitable means in holes 4^b.

In the bottom of boxing brace 4 I provide a boxing 4^a for the insertion of journal point 5^a of screw 5, said boxing 4^a of boxing brace 4, being in alignment with the hole provided in the flanged portion 2^b of shoulder boxing 2^a, for the purpose of holding the screw 5 in lineal alignment 25 with major plate 1, at all times.

I provide a jaw clamp traveling base 9 being an oblong square metallic block having centrally lineally disposed therein a threaded hole 9^a suited to the size and threads of screw 5, and intended to be mounted and to travel upon screw 5. The traveling base 9 is constructed with a square flange 9^b extending from one of its sides about half its length but flush with one of its ends centrally disposed between two of its sides and of height corresponding to the combined breadth of flange 3 and the thickness of major plate 1, and of width corresponding to the width of oblong slot 1^a of the major plate 30 1, the intent being that the top of flange 9^b shall when base 9 is mounted and traveling, be level with the surface of major plate 1, and that the flange 9^b fitting in slot 1^a shall prevent base 9 from turning when screw 5 35 inserted in hole 9^a is turned, thus causing base 9 to travel forward or backward corresponding to the turn of screw 5 therein. Flange 9^b is centrally provided with a hole 9^c disposed parallel to the threaded hole 9^a 40 as a means for securing the movable jaw clamp 10 thereon.

I provide a movable jaw clamp 10 for use in connection with traveling base 9 when mounted upon screw 5, and stationary clamp 55 11; which movable jaw clamp is composed of a metallic plate 10^a having on one side centrally disposed therein at right angles, a pin of size conformable to hole 9^c in flange 9^b of base 9, and for insertion therein; the 60 metallic plate having at one of its ends and at either edge flangedly disposed shoulders 10^d which taper upward forming a bit, the bit having its edge directioned toward the side opposite to the pin 10^b, the edge of the 65 bit being provided with multiple protrud-

ing teeth 10^e, the teeth protruding suitable to grasp the article worked upon. The shoulders 10^d are also directioned right-angularly outward and backward with the pin and are so constructed as to slope downward from the teeth 10^e in the direction with pin 10^b to intersect the right-angular line extending backward from the angle of the shoulder flange, the purpose being to form a flat bottomed head 10^e capable of resting flat upon the surface of major plate 1 when mounted, pin 10^b being positioned in plate 1, suitable so that the distance between pin 10^b and head 10^e will correspond to the distance between the hole 9^c and the top of flange 9^b of traveling base 9, the intent being to form a brace of shoulders 9^d and 9^e of base 9, and the bottom of head 10^e of jaw clamp 10 to take the strain off of screw 5 in operation.

I also provide a stationary jaw clamp 11, for use in connection with major plate 1, and minor plates 12 which stationary jaw clamp 11 is composed of a round metal button 11^a of size conformable to hole 12^b in minor plate 12 and not of greater diameter than the width of slot 1^a in major plate 1, the button 11^a having right-angularly protruding from one of its sides a rectangular oblong neck 11^b of length equaling the thickness of major plate 1, and minor plate 12, the sides and edges of rectangular oblong neck 11^b being of dimensions conformable to the rectangular offset 1^c in the point end of major plate 1, and to the rectangular offset 12^c in minor plate 12.

The sides and one of the edges of neck 11^b on the end opposite button 11^a are right-angularly flanged shoulders, the other edge the full length of the shoulder flanges being faced upward to form an oblong serrated bit 11^e having multiple teeth and of size conformable to the teeth of movable jaw clamp 10, the bottom of the shoulder flanges at the sides and edge of neck 11^b presenting broad flat surfaces suitable to cause them to lay flat upon the surface of major plate 1 and minor plate 12 when mounted and to cause a bracing effect between them and the flange of the button 11^a about neck 11^b. The top of the shoulder flanges from the serrated bit 11^e slopes backward to the line of the flange, the ends being rectangular. The serrated bit 11^e is directioned slightly forward protruding somewhat from the perpendicular outward in order to grasp the article worked upon. Stationary jaw clamp is mounted by inserting the button and neck in hole 12^b of minor plate 12 or the slot 1^a of major plate with the serrated bit 11^e directioned toward movable jaw clamp 10 and pressing the same backward until the right-angular neck 11^b engages in offset 12^c of minor plate 12 or offset 1^c of major plate 1.

I provide minor plate 12 for use when it

is desired to work upon articles longer than major plate 1. As many of them may be employed as is desired. In installation it is embedded in a groove formed in and so 5 made level with the surface of the work bench, the groove in the work bench being formed deep enough to admit and conformable to allow the insertion of button 11^a beneath the minor plate 12 in alignment with 10 hole 12^b and offset 12^c of minor plate 12.

Minor plate 12 is a metallic right-angular plate provided at each of its corners with construction hole means suitable for being secured to a work bench by screws or other 15 suitable means, and it is centrally provided with a key hole 12^b and 12^c of size and shape conformable to the neck 11^b and button 11^a of jaw clamp 11.

I claim:

20 1. A work bench vise consisting of a major plate, a stationary revolving screw mounted parallel therewith by means of boxings disposed beneath its ends; a jaw clamp base loosely mounted on the revolving screw; flange means for preventing the jaw clamp base from revolving with the screw; a movable jaw clamp provided with flanged shoulders, a serrated bit and laterally disposed pin fastening means loosely 25 mounted by hole means upon the flange of the jaw clamp base; handle means securely attached to the shank of the stationary re-

volving screw; boss means securely mounted upon the shank of the revolving screw between the threads and the boxing in which 35 the screw shank revolves; offset means provided in the end of the slot of the major plate for securing therein a stationary jaw clamp; a stationary jaw clamp having a button bottom, a flanged head having a serrated bit at its top, a right-angular neck interposed connectedly between its button bottom and flanged head; other plate means for securing the stationary jaw clamp in the surface of a work bench in such manner as to permit the stationary jaw clamp 40 to act conjunctively with the movable jaw clamp of the vise.

2. In a work bench vise having a stationary revolving screw, a major plate, a traveling jaw clamp base, a removable jaw clamp; the movable jaw clamp having a serrated bit, a flanged head having a flat bottom, a plate front, pin means attached to a plate front suited for insertion in corresponding 45 hole means in a clamp base, the plate front supporting a flanged head, the plate front suited to move snugly within an oblong slot, in a major plate.

WILLI FRANCK.
